JOHN C. SIMMONS, OF COLORADO SPRINGS, COLORADO.

ORE-ROASTING FURNACE.

1,164,761.

Specification of Letters Patent. Patented Dec. 21, 1915.

Application filed October 15, 1914. Serial No. 866,741.

To all whom it may concern:

Be it known that I, JOHN C. SIMMONS, a citizen of the United States, residing at 308 East San Miguel street, in the city of 5 Colorado Springs, in the county of El Paso and State of Colorado, have invented a new and useful Ore-Roasting Furnace, of which the following is a specification.

My invention relates to improvements in 10 ore roasting furnaces, in which an adjustable and oscillating air blast feed delivers the ore to be roasted in from above the flame and spreads it about broadcast through the flame upon a bed of roasted ore resting upon 15 a grate or rack comprising alternately and reversely oscillating grate bars beneath said bed adapted to scrape the underside of said bed and pulverize it; and some of the objects of my improvements are, first, to provide a controllable flame for the fire box or 20 roasting compartment 3^D; second, to provide means for sowing the mineral to be roasted, broadcast over and through said flame upon a bed of roasted ore in a manner under control 25 of the operator by automatic machinery; third, to provide a bed 4^C, of roasting ore in a body beneath the furnace roasting compartment proper; fourth, to provide means for holding back the flame from escaping 30 so as to retain the caloric of the flame within the roasting furnace; fifth, to provide a bed for the roasting ore where it will be kept hot from above and form into a compact 35 mass or semi-solid body as desired constantly accumulating at its top and being reduced to pulverized powder at its underside and provided to drop into a bin 6, below; sixth, to provide means for drawing from or for pulverizing the under- 40 side of said bed of roasted ore 4^C, by means of alternately oscillating grate bars 83, 83, and 84, 84, having flange teeth adapted to engage the underside of said bed; seventh, to provide means for forcing the flames in 45 the roasting furnace down against the top of the bed of roasting ore by downward draft from the top of the roasting furnace; eighth, to provide a roasting furnace having means for a continuous flow of ore to 50 the furnace from above in an unroasted state and having a continuous or intermittent grinding and removal of the ore after roasting from the underside of the bed of 55 roasted ore; ninth, to provide means for obviating the necessity of "drawing the

fire," or of stopping the continued process of roasting; tenth, to provide a supporting grate for said bed of roasted ore having its parts separately and easily removable and replaceable; eleventh, to provide a supporting grate of individual bars with means for cooling them, by circulating water or other fluid through longitudinal conduits in the bars. I attain these objects by means of the mechanism and appliances illustrated in the 60 accompanying drawings, in which—

Figure 1, is a side elevation of the entire roasting furnace with part of the masonry and construction removed to disclose the parts within and part of the construction 70 of the oscillating feed being removed; Fig. 2, is an elevation of the end of the roasting furnace showing part of the construction and masonry removed to disclose the parts within; Fig. 3, is a side elevation of the operating right arm 52, carrying the pitman 45; Fig. 4, is a side elevation of the disk wheel 46, carrying the pitman 45; Fig. 5, is a detailed sectional elevation of the hollow rocking sphere 10, and the lower part 80 of the air blast tube 11, showing its threaded adjustment vertically; Fig. 6, is a top view of the ratchet mechanism operating the pitman 25, and the sliding frame 22; Fig. 7, is a side elevation of the upright arm 19, of the rocking frame 20, showing a diagram of the end of the sliding frame 22; Fig. 8, is a top diagrammatic view of the sliding frame 22; Fig. 9, is a top diagrammatic view of part of the pitman 25, showing the socket mechanism to connect with the ball 33, of the sliding frame 22; Fig. 10, is a diagrammatic side view of part of the pitman 25, and the forked bearing 43; Fig. 11, is a side elevation of the side truss bar 89, with part of the middle removed and showing some of the parts beyond in position; Fig. 12, is a top view of Fig. 11, sectionized through on the line A—B. Fig. 13, is a perspective of one of the alternate 90 oscillating grate bars operated by the connecting rod 74, with the central portion removed; Fig. 14, is a perspective of one of the alternate oscillating grate bars operated by the connecting rod 71, with the central portion removed; Fig. 15, is a perspective of one of the side truss bars 89, showing part of the top and part of the center removed; Fig. 16, is a perspective on a large scale of one of the supporting block 100 105 110 115 120

bearings 85; Fig. 17, is a front elevation of the lower end of the supporting swing bar 72, supporting one end of the connecting rod 71, and one end of the eccentric pitman rod 66, where they are connected pivotally with the coupling pin 108; Fig. 18, is a perspective of the two connecting rods 71, and 74; Fig. 19, is a side elevation of the side of the joint shown in Fig. 17, showing the connection of the connecting rod 71, the supporting swing bar 72, and the upper eccentric pitman rod 66, with some parts cut away.

Similar letters and figures refer to similar parts throughout the several views.

The crown sheet 15, with the air blast tube 11, and its operating machinery on the top of the ore roasting furnace, the furnace proper consisting of mason work, the oscillating grate 5^b, and its operating mechanism and supporting the bed 4^c, of roasted ore constitute the outline or frame work of my invention.

At the top of a rectangular or roasting furnace with walls 1, of masonry surrounded by a dome-shaped roof is the crown sheet 15, having the concave bearing 57, supporting the hollow rocking sphere 10, which carries the feed mechanism to supply the ore from the hopper or supply bin 16, through the intake 13, 13, to the receptacle 103, within the hollow rocking sphere 10, where it is forced downward through the mineral passage-way 12, and into the roasting compartment 3^b, by means of an air blast from the lower end of the air blast tube 11. This air blast tube 11, is secured by adjustable threaded connection between the threaded sleeve 55, and the threaded adjusting nut 54, which is prevented from slipping by means of the lock nut 56. The threaded sleeve 55, is rigidly secured to the air blast tube 11, so that adjusting it, will also adjust the air blast tube 11. The ore from the supply bin 16, passing through the intake holes 13, 13, enters the receptacle 103, within the hollow rocking sphere 10, and passes down toward the mineral feed passage-way 12, and is forced through said passage-way by means of the air blast coming through the outlet 97, from the bottom of the air blast tube 11. This feed of the mineral depends partly upon the extent of the opening or space 104, between the lower end of the air blast tube 11, and is adjusted by means of the threaded nut 54, either raising or lowering the air blast tube 11, as shown in Fig. 5. The direction of the air blast passing down through the conduit 98, is changed so as to blow the ore over the surface or top 62, of the bed of roasted ore in a zigzag line in four directions by reason of the mechanism shown in Fig. 1, and Fig. 2, moving the top end of the air blast tube 11, by the use of the two pitmen 25, and 45, respectively

thrusting and pulling on a line at nearly right angles to each other. These motions in the four different directions are indicated by the dotted lines in Fig. 1, and in Fig. 2, showing the maximum oscillations of the top and bottom ends of the air blast tube 11, which carries with it in a rotating oscillation the hollow rocking sphere 10, resting upon the concave bearing 57, of the crown sheet 15, which forms a sort of a ball and socket joint. The thrust and pull motions of this air blast tube 11, as shown in Fig. 1, are operated by the mechanism shown in detail, in part, in Figs. 3, 6, 7, 8, 9, and 10, and the top of Fig. 1.

In Fig. 8, the sliding frame 22, carries a rocking pivot guide 34, supported in the frame with trunnions 105, 105, through which the top end of the air blast tube 11, projects upwardly and through which it works freely longitudinally, this sliding frame 22, is operated horizontally by the pitman 25, and slides on the slide bars 21, 21, of the rocking frame 20. The pitman 25, is connected with the sliding frame 22, by means of a ball and socket coupling comprising the ball 33, integral with the sliding frame 22, in Fig. 8, being engaged by the two socket cups 31, 31 on the ends of the spring shanks 32, 32, and being held in a loose rotatable connection by means of the clamping bolt 106, on the pitman 25. This pitman 25, has a steady forward motion toward the left as shown in Fig. 1, and an impulsive motion back to the right after the top of the free crank 27, is carried down to the left past a center line between the rotating shaft 35, and the pivot bearing 60, on the lower end of the thrusting spring 30. In Fig. 6, this free crank 27, is illustrated by a top view showing the pitman 25, bent to the left as though the top of the air blast tube 11, as shown in Fig. 1, had been thrust toward the observer to its maximum position.

The rotating to the left, on top, as shown in Fig. 1, of the ratchet wheel 23, carried rigidly secured to the rotating shaft 35, causes the ratchet teeth 28, 28, to engage the ratchet pawl 26, which is pivotally secured by means of the wrist pin 95, to the ratchet arm 39, of the free crank 27, and when the top of the free crank 27, will have reached a point on center between the rotating shaft 35, and the pivot bearing 60, the pivot bearing 60, will have been pushed far down and to the left and the thrusting spring 30, will have been bent from its normal form so that when the connecting pivot 41, is pushed below the center it will be forced back below the ratchet wheel 23, by the violent tension of the thrusting spring 30, and the ratchet pawl 26, will be released from, and will slide past under the ratchet teeth 28, 28, thus forcing the free crank 27, back beneath the ratchet wheel 23, as far as the thrusting

spring 30, will force it and thus violently forcing the top of the air blast 11, back to the right. As soon as the speed of the free crank 27, is slackened from the force of the 5 thrusting spring 30, the ratchet wheel 23, will reengage the ratchet pawl 26, with one of its ratchet teeth 28, and carry around with it the free crank 27, as before. While this motion imparted by the rotating shaft 10 35, is forcing the top of the air blast tube 11, to the left and right as shown in Fig. 1, the disk wheel 46, is forcing the top of the air blast tube 11, in a line at nearly right angles to said movement as shown in Fig. 2.

15 The rocking frame 20, which carries the sliding frame 22, has secured to its operating upright arm 52, by pivotal connection the pitman 45, connecting with it the disk wheel 46, operated by the driving shaft 110, which 20 disk wheel operates regularly to throw the top of the air blast tube 11, to the left and to the right while the mechanism shown in Fig. 1, is throwing it forward and backward.

25 The construction of the oscillating grate supporting the bed 4^c, is one of the principal inventions and essentials of my ore roasting furnace. In the side truss bars, 89, one of which is shown in part in Fig. 15, 30 there is a peculiar construction allowing the taking down of the grate bars, one at a time without removing the frame of their support or the bed 4^c. The key to the unlocking and removal of any one of the alternate oscillating grate bars 83, 83, and 84, 35 84, is the removable supporting block 85, which is supported by resting upon two of the supporting lug seats 87, 87, which are integral with the upright bars 88, 88. To 40 remove one of these bars it is necessary to remove the coupling pins 107, and 108, supporting the two connecting rods 71, and 74. Then remove the two connecting rods 71, and 74, and then take out the removable 45 supporting block bearings 85, 85, supporting on the supporting bearing 111, of the removable supporting block bearings 85, 85, the pivotal bearings 86, 86, of the alternate oscillating grate bar, desired to be removed, 50 which will allow the oscillating grate bar 83, 83, and 84, 84, to drop down through the upright slots 92, 92, when it can be removed beneath from the bin 6, below the oscillating grate 5^b. This form of removal of the grate 55 bars hereinabove described and the peculiar construction herein shown therefore is essential to the efficient operation of the grate. This allows one or more of the alternate oscillating grate bars 83, 83, and 84, 84, to 60 be removed without disturbing the bed 4^c, and without disturbing any part of the masonry or frame of the furnace.

In operating my ore roasting furnace the bed 4^c, is prepared in the usual way and 65 maintained continuously throughout the

process of roasting, constantly forming a deposit on the top surface 62, and constantly being pulverized at the bottom of the bed 4^c, of roasted ore, and having the pulverized particles being constantly 70 dropped into the bin 6, below, through the outlet recess 102, 102, between the bars 83, 83, and 84, 84.

The fire or flame proceeding from the flame 7, to the roasting compartment 3^D, 75 may be produced by a gas jet or by a flame from coal or oil or other fuel as desired and may be operated in conformity to the peculiar kind of fuel requirements applied.

In Fig. 2, is shown a form of oil burner 80 in which 61, represents the valve controlling the supply of fuel and 99, is the oil burner proper for controlling the supply of air for the flame. On the opposite side of the roasting compartment 3^D, is the outlet flue 9, 85 adapted to conduct the used gas from the roasting compartment 3^D, to be utilized in other parts of the plant of this nature until finally it escapes into the atmosphere. The outlet 8, from the roasting compartment 3^D, 90 is above the final outlet from the flue 9, so as to hold the hot air within the roasting compartment 3^D, so as to allow its caloric of high temperature to be transmitted to the ore to be roasted. This bed 4^c, is regulated 95 in its depth by regulating the amount of feed from 18^A, to build it up and by the rapidity of the grinding from its underside by means of the action of the alternate oscillating grate bars 83, 83, and 84, 84, beneath, reducing the bed from the underside. One of the peculiar advantages of this form of bed is that it holds the heat in the roasted ore in a body, and which body may be caked or held loosely as desired by governing the 100 depth of the bed and by governing the degree of heat. Another peculiar advantage is that the bed does not require to be stirred and lifted up, thus avoiding the evaporation of the precious mineral and thus preventing its escape through the outlet 9. Another peculiar advantage in the use of this form of operating of the bed 4^c, is the 105 continuous roasting operation without any cessation of roasting, for the purpose of 110 drawing a fire or removing the ore, etcetera.

In supplying the ore to be roasted into the furnace receptacle 3^D, I use the mechanism illustrated in 18^A, and shown in Fig. 1, and Fig. 2, with details of some of its parts 120 shown in Figs. 3, 4, 5, 6, 7, 8, 9, and 10. The ore is first prepared in the usual or desired way for roasting and is fed into the hopper or supply bin 16, in the bottom of which is the hollow rocking sphere 10, resting in the 125 concave annular bearing 57, and having a free rotary or rocking movement in all horizontal directions at its top. In the sides of the upper half of the hollow rocking sphere 10, are upright slot-shaped intake orifices 130

adapted to receive the ore from the supply bin 16, and convey it to the bottom of the receptacle 103, within the hollow rocking sphere 10.

5 The four-way rocking motion transmitted to the hollow rocking sphere 10, by the air blast tube 11, hereinbefore described causes the said sphere 10, to dip in four directions which assists in dipping up the ore from 10 various sides of the bottom of the funnel-shaped walls of the supply bin 16, and also tends to mix the ore within said sphere and to cause it to feed down to the feed passage-way 12, which is the outlet from said sphere 15 to the roasting compartment 3^P. One of the principal objects in this rocking motion is to direct the blast of the compressed air down through the hollow conduit 98, and through the outlet 97, in the bottom of the air blast 20 tube 11, so as to blow or shoot the mineral to be roasted through the mineral feed passage-way 12, in a constant stream that will zigzag across the top surface 62, of the bed 4^c, of roasted ore and through the flame and 25 heat of the roasting compartment 3^P. While the pitman 45, and its mechanism will cause this zigzag current to be in two directions, the pitman 25, will cause a zigzag current to be in two directions at nearly right angles 30 to the former zigzagging which will tend to distribute the ore evenly as desired by reason of the combination of the adjustment of the motions and especially from the pitman 45, which is adjustable in the slot 49, on the operating upright arm 52, by sliding the wrist 35 pin 48, up or down in said slot.

The racking frame 20, is composed in part of the upright arm 19, pivotally supported on the racking pivot 51, secured to one of 40 the supporting brackets 17, and the operating upright arm 52, pivotally supported on the racking pivot 50, secured to one of the supporting brackets 17, on the opposite side from the racking pivot 51, of the supply bin 45 16. These two upright arms 19, and 52, are connected at their top by means of the two slide bars 21, 21, which carry the sliding frame 22, having in each of its opposite longitudinal edges the two sliding grooves 24, 24, receiving and running upon the two parallel slide bars 21, 21.

55 The counter weights 14, 14, are for the usual purpose of balancing the superstructure sustained upon the rocking pivots 51, and 52. The pitman 29, connecting the connecting pivot 41, of the free crank 27, with the pivot bearing 60, of the thrusting spring 30, may have a longitudinal adjustment of a common form to adjust the pressure from 60 the spring 30. The compression spring 86, shown in Fig. 6, is adapted to hold the ratchet pawl 26, in contact position with the ratchet teeth 28, 28, at all times. The pivot bearings 37, and 38, shown in Fig. 6, 65 allow the free crank 27, to operate inde-

pendent of the rotating shaft 35. The pivot bearings 42, 42, work upon the same connecting pivot 41, as does the pitman 29, and connect the forked bearing 43, with the pitman 25, by means of the pivot connection 44, 70 and the clevis bows 53, 53.

This mechanism heretofore described and outlined in Fig. 1, operates to throw the flame across the roasting compartment 3^P, in two directions while the pitman 45, operated by the disk wheel 46, and secured thereto pivotally by means of the wrist pin 47, operates the feed mechanism in the direction across the line operated by the pitman 25. The disk wheel 46, is operated by the driving shaft 110, in the usual manner. 75

80 On the wrist pin 48, and turning with it is the thimble-shaped sleeve bearing 59, upon which one end of the pitman 45, is operated pivotally.

85 Pivotally operating in rocking movement in the sliding frame 22, is the guide sleeve 48, up through which the top of the air blast tube projects and loosely slides in its adjustment on the top of the hollow rocking sphere 10.

90 In each of the alternate oscillating grate bars 83, 83, and 84, 84, there is a longitudinal conduit 109, extending its full length and adapted to have supplied to one end a cooling fluid, as water and means for receiving said fluid out of the other end in a regular circulation to cool the respective bars and their contiguous parts. 95

99 The alternate oscillating grate bars 83, 100 and 84, are supported by their pivot bearings, 86, 86, resting upon the supporting bearing 111, in the removable supporting blocks 85, 85. The said bars are in two sets, which in this grate are represented by six 105 of the alternate oscillating grate bars 83, 83, and by five of the alternate oscillating grate bars 84, 84. Each of these bars is operated by downward projecting crank arms, the downward projecting crank arms 110 77, 77, operating the alternate oscillating grate bars 83, 83, and the downward projecting crank arms 87, 87, operating the alternate grate bars 84, 84. Near the lower end of each of the downward projecting crank arms 77, 77, and integral with the inside surface of said arms and projecting inwardly at right angles thereto are pivot lugs 79, 79, adapted to be received within the notched recesses 113, 113, on the under 115 edge of the connecting rod 71. Near the lower end of each of the downward projecting crank arms 78, 78, and integral with the outside surface of said arms and projecting outwardly at right angles thereto are pivot 120 lugs 80, 80, adapted to be received within the notched recesses 112, 112, on the under edge of the connecting rod 74. Said connecting rod 71, is supported at its free end 125 by the supporting swing bar 73, and the sup- 130

porting swing bar 72, supports the power end of the connecting rod 71, and also supports the end of the upper eccentric pitman rod 66, where it is connected by the coupling pin 5 108, with the supporting swing bar 72, and the connecting rod 71.

The operating shaft 65, shown in Fig. 1, carries integral therewith the upper eccentric cam wrist 68, carrying the upper eccentric cam 63, which operates the upper eccentric pitman 66, which in turn operates the connecting rod 71, which operates the alternate oscillating grate bars, 83, 83. On the same operating shaft 65, and turning therewith, is the lower eccentric cam wrist 69, carrying the lower eccentric cam 64, which operates the lower eccentric pitman rod 67, which in turn operates the connecting rod 74, which operates the downward projecting crank arms 78, 78, thus operating 20 the alternate oscillating grate bars 84, 84. The connecting rods 71, and 74, move in opposite directions at the same time and therefore cause the alternate oscillating grate 25 bars 83, 83, and 84, 84, to move toward each other on top and from each other on top alternately and thus causing the scraping flanges 100, 100, and the scraping projections 101, 101, to scrape loose particles of 30 the roasted ore from the under side of the bed 4^c, of roasted ore, when the ground particles will be forced down, by gravitation, through the outlet recesses 102, 102, between the said alternate oscillating grate 35 bars 83, and 84.

In Fig. 15, is shown a perspective on a large scale of one of the side truss bars 99, also shown in Fig. 1, and in Fig. 2. There are two of the side truss bars 89, one at 40 each side of the frame supporting the oscillating grate 5^b. These side truss bars 89, 89, support the alternate oscillating grate bars 83, 83, and 84, 84, as hereinbefore described. The top flange 90, of each of said 45 bars support the masonry for the two sides of the roasting furnace above. At the ends of the side truss bars 89, 89, and connected therewith, and at right angles thereto are the end truss bars 93, 93, one of which is 50 shown in Fig. 2, partly removed, and there showing the inside bottom flanges 91, 91, of the side truss bars 89, 89, supporting the upwardly bent ends 94, 94, of the bottom flange 70, of one of the end truss bars 93. 55 The top flange 114, of the end truss bars 93, assists in supporting the superstructure of masonry and the two end truss bars 93, 93, connect together the two side truss bars 89, 89, and form all together a rectangular 60 frame resting upon the wall of the bin 6, for the roasted and pulverized ore, and support on their top flanges the superstructure of masonry and the ore roasting furnace, proper.

65 The compartment of the furnace proper

is provided with a lining 96, of heat resisting material, inside the wall of masonry, for the usual purposes, of protecting the masonry.

The supporting flange 81, shown in Fig. 1, carries the supporting swing bar 75, supporting the power end of the connecting rod 74, and one end of the upper eccentric pitman rod 66, and also supports the swing bar 72, hereinbefore described. The supporting bracket 82, shown in Fig. 1, carries the supporting swing bar 76, supporting the free end of the connecting rod 74, and also supports the swing bar 73, supporting the free end of the connecting rod 71. 75

I am aware that prior to my invention, ore roasting furnaces have been used of various designs and somewhat similar in construction and objects; I do not therefore claim broadly ore roasting furnaces. 80

The top of the air blast tube 11, is supplied with air from an air compressor through a flexible tube in the common usual way.

The water or other cooling fluid hereinbefore mentioned is to be supplied to the conduits through the alternate oscillating grate bars 83, 83, and 84, 84, through any form of flexible tubes connecting with any available water supply. The connection of the 90 flexible tube or hose may be by a collar or otherwise as may be found expedient and convenient.

I claim—

1. A furnace of the class described, adapted for the roasting of ores, comprising a suitable receptacle, an intake flame on one side and an outlet flue on the opposite side and a racking grate near its bottom, in combination with an air blast feed at its top and 100 room for a bed of roasted ore upon said grate and below said flame, substantially as set forth and for the purposes specified.

2. In a furnace of the class described, adapted for the roasting of ores, a suitable 105 furnace receptacle, an intake flame appliance on one side and an outlet flue on the opposite side of said receptacle, a racking grate near its bottom, an air blast feed of ore at its top and a bed of roasted ore upon said 110 grate and below said flame, and adapted for a continuous feed-bed and outlet, substantially as set forth and for the purposes specified.

3. In a furnace of the class described, 115 adapted for the roasting of ores in a continuous bed built up at the top and ground away at the bottom, the combination of a suitable furnace receptacle, an appliance on one side to supply a suitable flame near the 120 top of the receptacle, a corresponding reverberating outlet flue on the opposite side of the receptacle, an oscillating air blast feed for the mineral from the top of said receptacle to the flame beneath and adapted to 125 130

distribute the mineral through said flame over the surface of a bed within said receptacle, and a rocking reducing grate supporting said bed, and means for operating said grate, substantially as set forth and for the purposes specified.

4. In a furnace of the class described, for the roasting of ores by a continuous process of feeding the intake and removing by gravitation at the outlet, a suitable roasting receptacle adapted to have the ore fed in at the top and to form a bed upon an oscillating grate beneath, a roasting flame fed in at one side of the receptacle near its top, an outlet flue at the opposite side of said receptacle from said flame, an oscillating feed appliance at the top of said receptacle adapted to feed the mineral to the furnace by an air blast directed to different parts of the furnace and bed beneath by means of two pitmen operating at right angles to each other and above said receptacle, adapted to deposit the mineral evenly over said bed while being roasted, and means for adjustably varying the amount of mineral fed by varying the aperture through which it is fed by means of threaded connection on the air blast tube, substantially as set forth and for the purposes specified.
5. In a roasting furnace of the class described, adapted for the roasting of ores by a continuous train of pulverized ore being fed into the furnace, baked into a bed and being ground away from the bottom of the bed as roasted and baked, comprising the combination of, a suitable roasting receptacle adapted to have the ore fed in at the top and to form a bed upon an oscillating grate beneath, a roasting flame fed in at one side of the receptacle near its top and above the bed an outlet flue with a downward exit at the opposite side of said receptacle from said flame, an oscillating feed appliance at the top of said receptacle adapted to feed the mineral to the furnace by an air blast into

the furnace chamber and said blast being directed to different parts of the furnace and bed beneath by means of pitmen operating at angles to each other and above said receptacle adapted to deposit the mineral evenly over said bed while being roasted, means for adjustably varying the amount of mineral fed through the air blast tube, eccentric operating means for rocking the bars of said grate alternately in opposite directions at the same time and adapted to pulverize the under side of said bed, substantially as set forth and for the purposes specified.

6. A furnace of the class described, adapted for the roasting of ores, comprising the combination of a suitable roasting receptacle adapted to have the ore fed in at the top and to form a bed upon oscillating grate bars beneath, means for feeding the pulverized ore in at the top of the receptacle spread in an even manner on said bed, a roasting flame fed in at one side of the receptacle near its top and above said bed, an outlet flue at the opposite side of said receptacle from said flame, an oscillating scraping grate beneath said bed comprising a gang of twisting and removable grate bars extending horizontally beneath said bed and resting upon removable trunnion blocks and being operated by removable connecting rods working each set of alternate grate bars in opposite directions by torsional movement, annular corrugated flanges on the respective upper sides of said grate bars adapted to scrape and cut the underside of said bed of ore and reduce it into fine particles, and openings for allowing said particles to fall through below said grate bars to a pit beneath, means for cooling said grate bars, substantially as set forth and for the purposes specified.

JOHN C. SIMMONS.
